US00D552595S

(12) **United States Design Patent** (10) **Patent No.:** **US D552,595 S**
(45) **Date of Patent:** **** Oct. 9, 2007**

(54) **CONTROL PANEL FOR A HEADSET**

(75) Inventors: **Andres Viduya**, Cranberry Township, PA (US); **Frank Singel**, Cranberry Township, PA (US); **James Wahl**, Export, PA (US); **Dominic Tooze**, London (GB)

(73) Assignee: **Vocollect, Inc.**, Pittsburgh, PA (US)

(**) Term: **14 Years**

(21) Appl. No.: **29/242,950**

(22) Filed: **Nov. 16, 2005**

(51) **LOC (8) Cl.** **14-01**

(52) **U.S. Cl.** **D14/205**; D14/217

(58) **Field of Classification Search** D14/205, D14/206, 218, 223, 192, 400, 188; D24/174, 307/149, 150, 156; 381/309, 370, 385, 347; 351/158; 455/344

See application file for complete search history.

Primary Examiner—Paula A. Greene

(74) *Attorney, Agent, or Firm*—Wood, Herron & Evans, LLP

(57) **CLAIM**

The ornamental design for a control panel for a headset, as shown and described.

DESCRIPTION

FIG. 1 is a front view of a control panel for a headset showing our new design;

FIG. 2 is another front view of the embodiment of FIG. 1; FIG. 3 is a cross-sectional view taken along lines 3—3 of FIG. 2;

FIG. 4 is a bottom view of the invention relative to FIG. 2; FIG. 5 is a right side view of the invention relative to FIG. 2;

FIG. 6 is a top view of the invention relative to FIG. 2; FIG. 7 is a left side view of the invention relative to FIG. 2; and,

FIG. 8 is a rear view of the invention relative to FIG. 2. The broken lines are for illustrative purposes only and forms no part of the claimed design.
